REFRIGERATION METHOD AND APPARATUS

Robert T. Brixxolara, New Dorp,
Staten Island, N. Y.

Application May 14, 1943, Serial No. 486,991

8 Claims. (Cl. 62—125)

This invention relates to refrigeration and relates more particularly to refrigeration systems in which volatile refrigerants are circulated between evaporators and condensers through the extraction of heat from the condensers by indirect contact with low temperature mediums.

In one embodiment of this invention an inclined flat walled plate condenser is placed in the lower portion of an insulated cabinet. A cold substance such as water ice or dry ice is placed upon the condenser for liquifying refrigerant vapor received from an evaporator exposed to a heat load. Liquid from the condenser drains by gravity into a receiver. The evaporator is located above the condenser and the refrigerant is lifted from the receiver to the evaporator by refrigerant vapor flowing through lift fittings.

A feature of this invention resides in controlling the refrigerating effect by flooding back liquid from the receiver into the condenser when it is desired to reduce or discontinue the refrigeration.

Another feature of this invention resides in supplying refrigerant vapor to the lift fittings from an evaporator located at a higher level.

Objects of the invention are to simplify and to improve the performance of refrigeration systems.

The invention will now be described with reference to the drawing which is a diagrammatic view with some of the components in section, of a refrigeration system embodying this invention.

The condenser 5 has thin metal walls, the upper and lower walls being parallel and relatively closely spaced and being inclined from the horizontal to permit drainage of liquid from the condenser. The condenser has the enlarged lower portion 6 which serves as an accumulator well.

The condenser is located within the insulated ice bunker 7 which contains dry or water ice 8 which rests upon the upper wall of the condenser and serves to extract heat from the refrigerant therein so as to liquify same.

The receiver 9 is located below the condenser and is connected with the accumulator well by the drain tube 10 through which the refrigerant liquid flows from the condenser into the receiver. The tube 10 terminates in the lower portion of the receiver. The receiver is also connected with the accumulator well 6 by the tube 11 which contains the valve 12 which is controlled by the thermostat 13 as will be described.

The drain tube 10 has a T-fitting 14 between the condenser and the receiver and the tube 15 is connected into this and into the lift fitting 16

and serves to supply refrigerant into the lift fitting 16.

The tube 17 connects the lift fitting 16 with the upper lift fitting 18 and the tube 19 connects the lift fitting 18 with the separator 20. The separator 20 is connected by the tube 21 to the evaporator 22. The evaporator 23 is connected to the evaporator 22 by the tube 24.

The suction tube 25 connects the upper portion of the evaporator 22 with the condenser 5 and serves to return vapor thereto to be condensed therein. The tube 26 connects the upper portion of the evaporator 23 with the upper portion of the lower lift fitting 16 and supplies vapor thereto for lifting the liquid refrigerant to the upper lift fitting 18 as will be described.

The evaporators 22 and 23 illustrated are thin rectangular plate type evaporators with metal walls such as are commonly used for chilling a space in which substances to be kept cool are stored. They could be tubes for air cooling purposes where it is desired to chill the air in air conditioning systems.

The system is charged as usual with a refrigerant of any well known type such, for example, as "Freon," methyl chloride or ammonia.

Since the temperature of the ice used for cooling the condenser, is the lowest temperature in the system, it will establish a condensing temperature which results in a corresponding pressure being established throughout the system, which pressure depends upon the characteristics of the refrigerant used, upon the temperature of the ice used and the extent of surface contact. This is true however, only when the condenser serves truly as such and is drained of liquid. If the condenser fills with liquid, it ceases to condense vapor and serves only to precool the liquid contained therein. When this condition exists the pressure within the system depends only upon the temperature of the evaporators and upon the ambient temperature of the space to which they are exposed.

The condenser 5 is sloped as illustrated to aid in drainage and the drainage level may be so set that the lower or drainage end of the condenser acts as a refrigerant liquid precooler.

The liquid upon condensing drains into the receiver 9 and is carried through the tube 15 into the lift fitting 16 where a liquid level is established at the same height as is in the condenser (shown as h on the drawing).

The liquid draining into the receiver 9 is conducted to the bottom. This receiver which is a metal cylinder, has a capacity to contain enough

refrigerant to equal the total contents of the condenser, the lift fitting, and the interconnecting piping. It may be small since its capacity need be but a fraction of that of the entire system. The receiver may be located within the refrigerated space or outside same. It will be exposed to air having a higher temperature than the temperature of the refrigerant within it which will warm up upon filling and the warmed liquid rising through the tube 11 into the accumulator well 6 where it is cooled and other liquid replaces it.

If the heat reaching the receiver 9 is excessive or the accumulator well 6 is devoid of liquid, some vapor will form in the receiver and will pass into the condenser to recondense. It is intended that the receiver shall be of such size and have such exposure that the amount of precooling in the drainage portion of the condenser be dissipated by the exposure of the receiver to the air in a space having a warmer ambient temperature.

The lift fittings 16 and 18 are small cylinders which use refrigerant vapor to lift the refrigerant to the higher placed evaporators. A source of vapor pressure must be introduced which pressure must be greater than the terminal pressure on the tube 19, the separator 20 and the evaporator 22 but not greater than that of the liquid column h which column serves as a seal against the vapor blowing back into the condenser. This pressure is obtained through the tube 26 from the evaporator 23 and is the pressure of the evaporated refrigerant. The vapor depresses the liquid in the fitting 16 and blows through the tube 17 forming bubbles and lifting the liquid. This column of rising bubbles and entrained liquid terminates in the separator 20 and the liquid and vapor separate therein.

The liquid in the evaporator 22 evaporates in due course since its temperature and pressure relations are such that it absorbs heat from the space it serves. Liquid from the evaporator passes through the tube 24 into the evaporator 23. The liquid in the evaporator establishes itself to have a height which is less than that of the liquid in the evaporator 22 by the amount h . This difference in height is caused by the resistance through the lift operation previously described. The evaporated vapor in the evaporator 23 must overcome this resistance. Since the vapor pressure in the evaporator 22 is less than in the evaporator 23, the liquid level in the evaporator 23 must be lower. The differential pressure corresponding to h is such as to blow through the lift resistance and into the condenser.

The process of evaporation having reduced the ambient temperature to that desired, the evaporating cycle must be stopped to check further cooling. This is accomplished according to this invention by control of the valve 12 by the thermostatic bulb 13 which may be placed in contact with the evaporator or in the space being refrigerated. When the thermostat closes the valve, the liquid in the receiver continues to absorb heat, to warm up and then to vaporize. The vapor escape through the tube 11 being checked by the valve 12, builds up and floods liquid back through the tube 18 into the condenser and into the lift fitting 16. In flooding back into the lift fitting it reduces its pumping capacity by deepening the liquid seal. Due to the flooding of the condenser, it ceases to be a condenser and evaporation in the evaporators 22 and 23 ceases. The liquid in the condenser precools but does not establish a pressure relationship for the system.

It merely becomes sub-cooled liquid at the system pressure established by the evaporators.

Complete flooding of the condenser discontinues evaporation. Partial flooding reduces the evaporation. Thus the valve 12 may be an on-off valve or it may be of the modulating type for graduated control. In the annexed claims flooding means partial or complete flooding.

In due course, through the refrigerated space rising in temperature, the thermostatic valve 12 opens through the influence of bulb 13. With this occurrence the vapor trapped in the receiver 9 is released through the tube 11 and liquid in the condenser drains into it to fill it and in so doing exposes the condenser surface again to serve as a condenser and as a means for dropping the evaporator pressures and thus reestablish the evaporation cycle for cooling. The control described in the foregoing does not involve disturbing the volume of the liquid in the evaporator.

The ice and the condenser in the system described in the foregoing correspond to the compressor in a mechanical system. In a mechanical system, the capacity of the compressor is the limitation on how low a pressure the evaporator can be pulled down to and thereby its temperature. But in the ice system described herein any desired low pressure can be attained by increasing the size of the condenser which can melt and absorb heat from the ice at any rate impressed upon it.

While this invention has been described in connection with the use of ice or other stored source of cold for absorbing heat from a condenser, it is to be understood that certain features are not limited to use in such a system but may be used in a mechanical system.

While one embodiment of the invention has been described for the purpose of illustration, it should be understood that the invention is not limited to the exact apparatus and arrangement of apparatus illustrated as modifications thereof may suggest themselves to those skilled in the art without departure from the essence of the invention.

What is claimed is:

1. A refrigeration system including an evaporator, a condenser, and a liquid receiver connected in a refrigerant circuit, said receiver being located below said condenser, a tube for draining liquid from said condenser into said receiver, a separate tube for conducting vapor from said receiver back to said condenser, and means for throttling said separate tube for causing liquid from said receiver to flood back through said first mentioned tube into said condenser when a desired condition is brought about by the evaporation of refrigerant in said evaporator.

2. A refrigeration system including an evaporator, a condenser, and a liquid receiver connected in a refrigerant circuit, said receiver being located below said condenser, a tube for draining liquid from said condenser into said receiver, a separate tube for conducting vapor from said receiver back to said condenser, and means including means responsive to a condition brought about by the evaporation of refrigerant in said evaporator for throttling said separate tube for causing liquid from said receiver to flood back through said first mentioned tube into said condenser.

3. The method of controlling a refrigeration system including a condenser, a receiver and an evaporator, which comprises using vapor from

said receiver for flooding back liquid from said receiver into said condenser for reducing the evaporation of liquid in said evaporator.

4. The method of controlling a refrigeration system including a condenser, a receiver and an evaporator, which comprises supplying liquid from said condenser into said receiver and using vapor from said receiver for flooding back liquid from said receiver into said condenser, and controlling such supply of vapor in response to a condition brought about by the evaporation of liquid in said evaporator.

5. A refrigeration system including an evaporator, a condenser, and a liquid receiver connected in a refrigerant circuit, said receiver being located below said condenser, a tube for draining liquid from said condenser into said receiver, a separate tube for conducting vapor from said receiver back to said condenser, means for throttling said separate tube for causing liquid from said receiver to flood back through said first mentioned tube into said condenser when a desired condition is brought about by the evaporation of refrigerant in said evaporator, and means including means utilizing refrigerant vapor for lifting liquid from said receiver to said evaporator.

6. A refrigeration system including an evaporator, a condenser, and a liquid receiver connected in a refrigerant circuit, said receiver being located below said condenser, a tube for draining liquid from said condenser into said receiver, a separate tube for conducting vapor from said receiver back to said condenser, means in-

cluding means responsive to a condition brought about by the evaporation of refrigerant in said evaporator for throttling said separate tube for causing liquid from said receiver to flood back through said first mentioned tube into said condenser, and means including means utilizing refrigerant vapor for lifting liquid from said receiver to said evaporator.

7. A refrigeration system including an evaporator, a condenser, and a liquid receiver connected in a refrigerant circuit, said receiver being located below said condenser, means for draining liquid from said condenser into said receiver, said condenser being inclined at an oblique angle to the horizontal whereby drainage of liquid therefrom into said receiver is facilitated, means for flooding liquid back from said receiver into said condenser, and means responsive to a condition brought about by the evaporation of liquid in said evaporator for controlling said flooding and draining means.

8. A refrigeration system including an evaporator, a condenser, and a liquid receiver connected in a refrigerant circuit, said receiver being located below said condenser, said condenser being inclined at an oblique angle to the horizontal and having a liquid precooler formed at the lower end thereof, means for draining liquid from said precooler into said receiver, and means including means responsive to a condition brought about by the evaporation of liquid in said evaporator for flooding back liquid from said receiver into said precooler.
